UNITED STATES PATENT OFFICE.

ELMER S. SALYARDS, OF MOLINE, ILLINOIS.

COAL-DUST-FEED MECHANISM.

Application filed November 12, 1925. Serial No. 68,551.

My invention has reference to an apparatus for feeding powdered fuel, such as coal dust, into a stove or furnace, it having been demonstrated that when said dust is injected in the form of a spray, and when mixed with a quantity of air, it is in a very combustible form, and burns with an excessive amount of heat. The chief purpose of the present invention is to produce a device for handling and injecting the powdered fuel which possesses a great degree of efficiency.

Another purpose of the invention is to provide a novel means for regulating the feed of the material, so as to increase or diminish the same, as desired.

Another object thereof is to provide a receptacle, or magazine for the material of a novel form, provided with means for a constant movement of the material while the machine is in operation, and which magazine is removable from the machine, so that two or more of such magazines can be used, one of which is being filled while the other is in use.

Another purpose of the invention is to keep the material tightly enclosed while in the machine, so that the fine powder will not escape, and permeate the atmosphere surrounding the machine.

The above named, and other features and advantages of the invention will more fully appear from the following specification, reference being had to the accompanying drawings, in which;

Fig. 1 is a plan view of the machine, with the magazine removed.

Fig. 2 is a side elevation thereof, with some of the parts broken away.

Fig. 3 shows the machine in vertical section.

Fig. 4 is a cross-section, on the broken line 4-4 of Fig. 3.

The reference number 1 indicates a bed-plate, upon which is mounted a rotary fan 2, of usual construction, with which is connected a discharge pipe 3, fitted with a nozzle 4, designed to be inserted in the casing of a furnace, a fragmentary part of which is shown at 5. The fan is operated by means of a motor 6, through a drive-shaft 7.

Supported adjacent to the fan 2 is a casing 9, communicating with said fan through an opening 10 in the walls of the casing and fan. (Fig. 3.) In the upper part of said casing is a cross-piece 11, supporting an endless chain 12, passing round a pair of wheels

13 on shafts 14 and 15 rotatably mounted in the casing 9. The shaft 14 is projected beyond the casing in a bearing 16, and on the outer end of said shaft is fixed a friction disk 17, engaged by an idler disk 18, driven by a disk 19 on one end of a shaft 20, journalled in bearings 21 supported from the fan casing. The shaft 20 is parallel with the shaft 7, and adapted to be driven therefrom by means of a gear-wheel 22 on the shaft 20 and gear-pinion 23 on the shaft 7, in mesh with said wheel. The idler disk 18 is supported on a rod 25, so as to rotate freely thereon, the upper part of said shaft 14 being threaded and passing through an opening in the upper end of a support 26, mounted on the bed-plate 1. The rod 25 is held in place by a pair of set-nuts 27 and 28, on opposite sides of the support 26. The lower end of the rod 25 is formed into a fork 29 held slidably in channelled portions of the bearing 16.

By means of the last-named mechanism the movement of the shaft 7 is imparted to the shaft 14, causing a movement of the chain 12 along the cross-piece 11 toward the inner end thereof. The relative size of the wheels 22 and 23 and of the disks 17, 18, and 19 is such that the shaft 14 is caused to rotate at a greatly reduced rate of speed, and the movement of the chain 12 is correspondingly slow. By a proper adjustment of the nuts 27 and 28 the position of the disk 18 may be shifted outwardly or inwardly, as desired, causing a proportionate decrease or increase in the speed of the disk 17, and of the chain 12, for the purposes hereinafter pointed out. A constant operating contact of the train of disk wheels is compelled by means of a coiled spring 30 on the shaft 20, between the hub of the disk 19 and bearing 21.

Supported on the casing 9 is a hopper 32, the lower part of which is funnel shaped, and ends in a foot 33, which fits between side flanges of the casing. The hopper may be otherwise braced to prevent its upsetting. In the lower end of the hopper, just above the chain 12, is an opening 34, permitting material in the hopper to pass downwardly onto the chain, which operates in a channel 35, formed partly in the upper face of the cross-piece 11, and partly in the lower face of the foot 33. Fine material of the kind hereinbefore mentioned which is fed downwardly onto the chain is carried along

thereby until it reaches an opening 36 in the part 11, through which it passes, and is then drawn through the opening 10 into the fan by a current of air coming from the open end 37 of the casing 9. The combined dust and air is then forced through the pipe 3 and dispersed into the furnace in a gas-like combustible volume. The amount of air which is mixed with the powdered material 10 may be controlled by means of a shutter 38 hinged at one side of the open end of the casing.

In the lower part of the hopper 32 is a cone 40, provided with one or more openings 41, and rotatably mounted centrally of said cone is a vertical shaft 42, to which is fixed a cone-shaped shutter 43, having one or more openings 44, adapted to register with the opening 41 upon the shaft 42 being 20 rotated. On the upper end of the shaft 42 is a bevel-gear wheel 45, in mesh with a similar wheel 46 fixed on a shaft 47 rotatably mounted in the upper part of the hopper. On one end of said shaft is a sprocket-wheel 48, (broken lines) connected by a sprocket chain 49 with a similar wheel 50 on the end of the shaft 20. When said shaft is in operation movement is thereby imparted to the shaft 42, to cause a continuous 30 rotation thereof. Fixed in the shaft 42 are rods 51, which stir the material in the hopper, and prevents the packing thereof. The end of the shaft below the cone 40 is provided with rods 52 for a similar purpose. The 35 top of the hopper is closed by a cover 53.

The hopper 32 serves as a receptacle, or magazine, capable of holding a considerable quantity of powdered coal, or similar material, which is fed gradually downward to 40 and into the casing 9, wherein it is delivered to the fan in the manner hereinbefore described. The amount of material that is fed into the fan is determined by the speed of the chain 12, and as hereinbefore set 45 forth, the speed of said chain can be regulated by an adjustment of the position of the idler disk 18.

By reason of the hopper 32 being removably mounted in the machine it is possible 50 to make use of two or more of such receptacles, one of which is charged while the other is in use. In removing a hopper from the machine it is necessary to first disconnect the chain 49, and replace it on a similar wheel 48 on the other hopper, it being 55 of course necessary to duplicate the internal mechanism of the hopper in all of the receptacles. At such time as the hopper is being filled the shutter 43 is turned to a position 60 to close the openings in the cone 40. The

cone and shutter mechanism not only provide a constant feed for the material when the machine is in operation, but they form a guard for the lower end of the hopper, preventing the material being packed there-in by the weight of the main body thereof, so as to become immovable. The space below the cone forms a separate feed chamber. 65

It will be observed that the fan mechanism and feed devices are in close relation, 70 so that there is a direct delivery of the material to the fan. The parts are also compact, and fully enclosed, reducing the danger of escape of the dust to a minimum. By means of the machine herein shown and 75 set forth it is possible to make use of a relatively cheap class of fuel in the production of heat.

What I claim, and desire to secure by Letters Patent, is:

1. In a device of the class described, a rotary fan and drive-shaft therefor, a casing connected with said fan and opening directly into the same, a support in said casing having a restricted vent in proximity to such opening, a hopper provided with a plate adapted to rest on said support, said plate and support having a common channel, into which said hopper opens, a continuous chain mechanism operating in 90 said channel, and means for driving said chain at a reduced rate of speed.

2. A device of the class described, comprising a casing and endless conveyor for powdered material therein, a magazine for 95 powdered material removably supported on said casing, in position to discharge its contents into said casing, an intermittent feed mechanism in the lower part of said magazine, capable of being closed when the 100 magazine is detached from the machine, means for operating said endless conveyor, and means for actuating said feed mechanism coincidently with the operation thereof.

3. In a device of the class described, an enclosed magazine for powdered fuel having a funnel-shaped lower portion and discharge opening therefrom, a cone-shaped shell in the lower part of said magazine, provided with one or more passages, a rotating shutter for said shell, and means for the operation thereof, agitating devices in said magazine, above and below said shell, and a conveyor mechanism for the contents of said magazine, adapted for attachment to the lower end thereof.

In testimony whereof I affix my signature.

ELMER S. SALYARDS.
